Primary Examiner — Jack Reickel*Assistant Examiner* — Bobby W Jones, II(74) *Attorney, Agent, or Firm* — Gardner, Linn, Burkhardt & Ondersma LLP(57) **CLAIM**

The ornamental design for a portable water treatment device, as shown and described.

DESCRIPTION

FIG. 1 is a top, right perspective view of a portable water treatment device embodying the new design;

FIG. 2 is a top, rear perspective view thereof;

FIG. 3 is a bottom, right perspective view thereof;

FIG. 4 is a front view thereof;

FIG. 5 is a rear view thereof;

FIG. 6 is a right view thereof;

FIG. 7 is a left view thereof;

FIG. 8 is a top view thereof; and,

FIG. 9 is a bottom view thereof.

FIGS. 1-9 show portion of the portable water treatment device in broken lines. The broken line portions form no part of the claimed design.

1 Claim, 9 Drawing Sheets(56)
